[57] CLAIM

The ornamental design for a snow thrower housing, as shown and described.

DESCRIPTION

FIG. 1 is a perspective view of a snow thrower housing embodying our new design;

FIG. 2 is a left side elevational view thereof;

FIG. 3 is a front elevational view thereof;

FIG. 4 is a top plan view thereof;

FIG. 5 is a bottom plan view thereof; and

FIG. 6 is a rear elevational view thereof.

The broken lines in FIG 1 of the drawings are for illustrative purposes only.
